INSTRUMENT MOUNTING AND AN ELEMENT
THEREOF

Harry S. Pastureczak, East Moline, Ill.

Application October 12, 1951, Serial No. 251,016

9 Claims. (Cl. 248—183)

1

The present invention relates to instrument mountings for adjustably supporting instruments of various kinds, especially cameras and optical instruments such as telescopes, binoculars and the like.

The invention is designed as an improvement over the instrument mounting shown and described in my prior Patent No. 2,524,473, dated October 3, 1950, for Instrument Mounting. In this patent there is illustrated an instrument mounting of the type in which the instrument is capable of adjustment about both vertical and horizontal axes, together with means for holding or locking the instrument in any desired position of adjustment relative to both the vertical and the horizontal axes. Selectively operable trigger-operated releasing means are provided which is capable of being set or conditioned so that, upon operation of the trigger, the locking means which holds the instrument against both horizontal and vertical swinging movements are simultaneously released to permit universal adjustment of the instrument. Alternatively, the trigger-operated releasing means is capable of being conditioned or set so that the locking means which holds the instrument against panoramic swinging movement in azimuth is permanently disabled and does not come under the control of the trigger so that the latter may control only the locking means which holds the instrument against tilting movements in elevation about a horizontal axis.

The structure and function of the present invention is generally similar to the structure and function of the invention shown and described in the above-mentioned patent, but in the present instance certain refinements have been incorporated which render the instrument mounting more efficient in its operation, more readily susceptible to economical manufacture and simpler to manipulate in attaining the desired function. It is therefore among the principal objects of the present invention to improve instrument mountings of the character shown in the above patent in various respects so as to simplify the construction of the various parts, to improve their cooperative action, as well as to facilitate their manipulation when in use.

Briefly, the instrument mounting shown in the above-mentioned patent includes among other things an elbow structure having a vertical leg and a horizontal arm and on which the instrument is mounted by means of suitable supporting mechanism. The elbow is capable of rotation about its vertical leg to attain horizontal swing-

2

ing movement or panoramic sweep of the instrument and the supporting structure for the instrument is rotatable about the horizontal arm to attain horizontal tilting adjustment of the instrument. The elbow is split longitudinally through the middle and the metal of the elbow at the split edges thereof is relieved on both sides of the base of the elbow to provide a rocking or fulcrum axis which functions, when the split sections of the horizontal arm are brought together to spread the split sections of the vertical leg and vice-versa. When the split sections of the horizontal arm are compressed or brought together, the consequent spreading of the split sections of the vertical leg causes them to bind against the inner wall of the tubular mounting of the elbow so that the latter is locked against rotation about a vertical axis and so that the instrument itself is held against panoramic sweeping movements.

The structure of this patent further includes trigger-operated locking means which is normally effective to maintain the sections of the horizontal arm of the split elbow in a contracted or compressed condition so as to spread the sections of the vertical leg against the wall of the elbow mounting and thus lock the elbow against turning movement about the axis of the vertical leg. The trigger operated locking means is capable, upon operation of the trigger thereof, to release the compressional forces normally applied to the sections of the horizontal arm so as to relieve the binding action of the sections of the vertical leg upon the wall of the elbow mounting and permit turning movement of the elbow about a vertical axis. Control means are provided for permanently spreading the sections of the horizontal arm so as to positively contract the sections of the vertical leg and thus render the trigger operated locking means incapable of spreading them so that panoramic sweeping movements of the instrument are available regardless of the operation of the trigger-operated locking means which, under such conditions, is effective only to control the locking or releasing of the instrument against tilting movements in elevation about a horizontal axis. The present invention involves an improved form of split elbow structure, together with an improved co-operating spreading means for effecting spreading of the split sections of the horizontal arm thereof wherein the operations of machining the various parts involved are greatly simplified.

The provision of an elbow construction and of a spreading means therefor of the character

briefly outlined above being among the principal objects of the present invention, another object thereof is to provide such a spreading mechanism which will accomplish the functions of the earlier mechanism in a simplified manner and with less complexity of manual control.

Another object of the invention is to provide an instrument mounting of the character briefly outlined above in which the mating sections of the split elbow are inherently in themselves held against axial shifting movement along one leg of the elbow and in which the fulcrum axis is incapable of shifting.

Another object of the invention is to provide a novel method of forming split elbow constructions designed for use in connection with instrument mountings in the manner indicated briefly above.

Other objects of the invention not at this time enumerated will become readily apparent as the nature of the invention is better understood.

In the accompanying three sheets of drawings forming a part of this specification, one embodiment of the invention has been shown.

In these drawings:

Fig. 1 is a side elevational view of an instrument mounting constructed in accordance with the principles of the present invention;

Fig. 2 is a fragmentary side elevational view of the structure shown in Fig. 1 as viewed from the left hand side thereof and showing the same mounted on a tripod or similar support;

Fig. 3 is a side elevational view similar to Fig. 2 with certain parts thereof being shown in section to more clearly reveal the nature of the invention;

Fig. 4 is a sectional view taken substantially along the line 4—4 of Fig. 2;

Fig. 5 is a sectional view taken substantially along the line 5—5 of Fig. 1;

Fig. 6 is a sectional view similar to Fig. 5 with the parts shown in a different position;

Fig. 7 is a composite view including a sectional view taken substantially along line 7—7 of Fig. 5 and an end elevation of the lock control mechanism when conditioned in accordance with the disclosure of Fig. 5;

Fig. 8 is a composite view including a sectional view taken substantially along the line 8—8 of Fig. 6 and a side elevational view of the lock control mechanism when conditioned in accordance with the disclosure of Fig. 6;

Fig. 9 is an expanded end elevational view of a split elbow construction employed in connection with the present invention.

Fig. 10 shows full size views, in elevation, of the inner faces of both sections of a split elbow forming a part of my invention, the said views illustrating portions of a fractured vertical rib on each section, whereby the rib in the assembled relation of the elbow sections constitutes a fulcrum for pivotal movement of said sections.

Fig. 11 is a full size plan view of the elbow section shown in Fig. 10 arranged in the assembled relation shown in Fig. 5, the ends of the horizontal arm of the elbow being moved together to emphasize the pivotal action of the elbow sections with respect to each other; and

Fig. 12 is a view similar to Fig. 11, but illustrating the elbow sections moved to another position about their fulcrum axis.

The improved instrument mounting comprising the present invention involves in its general organization a two-piece split fitting or elbow 10 which, when assembled in the instrument

mounting, includes a composite vertical leg 12, a composite horizontal arm 14 and a composite connecting elbow portion 16. The leg 12 is telescopically received and supported in a base socket member 18 in which it is retained by means of a keeper screw 20 which extends through the base and into an annular groove 22 provided near the lower end of the leg 12. The elbow 10 is thus capable of rotational movements about the vertical axis of the socket member 18 for panoramic sweeping movements of the camera or other instrument as will be described presently. The arm 14 receives thereover a self-braking locking collar 24 on which the instrument is adjustably mounted and the locking collar is capable of tilting movements about the horizontal axis of the arm 14, when released for such tilting movement, or of being locked to the arm 14 against tilting movement thereon in a manner and for a purpose that also will be set forth presently.

The adjustable mounting for the instrument on the locking collar assembly 24 forms no part of the present invention and reference may be

had to the above mentioned patent for a full disclosure thereof. However, for convenience of description it may be stated briefly that this mounting includes an instrument-supporting assembly 25 having a adjustable pad 26 providing a seat on which the instrument, which may be a camera (not shown), is clamped. The pad 26 provided with the usual instrument stud and thumb wheel assembly 28. The locking collar assembly 24 includes an upper offset apertured lug 32 on which the assembly 25 is adjustably mounted and to which it is adapted to be adjustably clamped by means of a clamping knob 34.

Referring now to Figs. 2, 3 and 9, the split elbow 10 comprises two separable, similar and complementary L-shaped sections 36 and 38. The two sections 36 and 38 are initially formed in one piece as a unit, as for example, by a die casting operation and finished to form an elbow fitting in which the two sections are maintained spaced from each other by means of a relatively thin, elongated, frangible connecting web 40 (Figs. 3 and 9) which extends vertically along two opposed edges of the leg portion 12 and transversely across the horizontal arm 14 and across the elbow portion 16. The vertical leg portion 12 is, for convenience and lightness, relieved as at 42 to provide an internal vertical bore and the arm 14 is similarly relieved as at 44 with the two relieved portions being separated by a channel 46 in the metal across which the frangible web 40 extends. The initially formed or cast elbow is split longitudinally along the major outside surface thereof to provide a pair of opposed surfaces 48 and 50 which extend from the lower end of the leg 12 around the elbow portion 16 to the end of the arm 14. The split in the outer side of the initially formed or cast elbow is interrupted only by the vertically extending web 40 (see Figs. 5 and 6). The lower wall of the arm 14 is split as at 52 along a minor region diametrically opposed to the major split portion of the elbow and thus, in the initially formed or cast article, the two sections 36 and 38 thereof are maintained slightly spaced from each other with the frangible web 40 constituting the sole inter-connecting means between these two initially integral parts.

The frangible web is broken along its length and this is readily accomplished by the simple procedure of misaligning the two sections 36 and

38 by applying spreading pressure thereto sufficient to fracture the web along an irregular line as clearly shown by the stippling of Fig. 3 and which fracture also appears in Figs. 9, 10, 11 and 12 where the two parts 36 and 38 are separated from each other. A portion of the fractured web 40 also appears in Fig. 1.

The web 40, when fractured in the manner set forth above, constitutes an elongated fulcrum by means of which the two parts when assembled upon each other in the instrument mounting may be rocked to a slight degree relative to each other. In the assembled structure a resilient gasket 54 may be inserted between the two parts 36 and 38 at the base of the arm 14 (Figs. 3 and 4) and a second resilient gasket 56 may extend between the opposed faces 48 and 50 of the sections along the opposed faces of the elbow portion 16 to limit or restrain the rocking movement between the two sections.

From the above description, it will be seen that when the composite arm 14 is compressed so as to rock the sections 36 and 38 about the fulcrum axis of the web 40 and bring the outer ends of the arms toward each other as shown in Figs. 5, 7, 11 and 12, there will be a widening of the distance between the opposed surfaces 48 and 50 of the composite leg 12, thus in effect, increasing the diameter of the composite leg 12 by a spreading action so that the outside surfaces of the two parts 36 and 38 will bear against the inner surface of the base socket 18 and bind the leg 12 in the socket 18 to prevent rotational movement of the elbow structure 10 as a whole about a vertical axis. Upon release of compressional force on the composite arm 14, the resilient gasket 54 in a measure serves as a cushion buffer between the two sections 36 and 38 of the arm so as to hold them in proper position to facilitate turning movement of the elbow about the vertical axis of the leg 12.

Inasmuch as the two sections 36 and 38 of the split elbow in the regions of the leg 12 are closely encased within the vertically extending cylindrical confines of the base socket, there is little opportunity for the opposed contiguous fracture areas of the web 40 to become separated to a degree sufficient to permit longitudinal shifting movement of one section relative to the other. The opposed fractured areas are precisely, and even the microscopically small ridges of the one extend into the valleys of the other and vice versa and the only relative movement between these two opposed surfaces is an extremely limited rocking movement.

By the same token, the so-called "spreading" or "contracting" movements of the sections of the composite split leg 12 is the result of such tilting or rocking movement between the sections on the fulcrum axis of the web 40 wherein the surfaces 48 and 50 recede from or approach each other respectively. The "spreading" and "contracting" movements of the sections of the split arm 14, however, is of a different nature. In this instance, since the axis of the fractured web 40 is perpendicular to the axis of the composite split arm 14, rocking of the two sections 36 and 38 will effect equal recession and approach of the surfaces 48 and 50 and of the opposed surfaces along the split portion 52.

Referring now to Figs. 1 and 4, the locking collar 24 includes a body portion 60 provided with a transverse opening 62 therein through which the composite split arm 14 of the elbow 10 extends and on which arm the locking collar is

supported for angular tilting movement about a horizontal axis. The body 16 includes a yieldable friction band 64 which is split medially and circumferentially therearound as at 65 (Fig. 2) and which encompass the arm 14 and is movable into and out of clamping engagement with the latter. The straps or sections of the split band 64 are resilient and are normally sprung outwardly so as to relieve their gripping action on the split arm 14 and they are capable of being forced into gripping engagement with the arm in the manner of a brake band by means of a pair of attachment lugs 66 which are operatively connected through a train of mechanism about to be described to a compression spring 68 associated with an operating handle or pistol grip assembly 70.

The pistol grip assembly 70 includes a barrel portion 72, the forward end of which projects through a sleeve or thrust bushing 74 yieldingly and frictionally held in an offset apertured lug 76 provided on the body portion of the locking assembly 24. The barrel 72 projects into the casing 77 of the pistol grip assembly and is provided with a clearance slot 78 through which there extends the upper end of a trigger member 80 which is pivoted as at 82 to the casing 77 and which depends from the latter. The casing 77 is provided with a trigger handle 84 in which the trigger 80 is guided. The sleeve 74 and barrel 72 are secured together against relative turning movement by means of a pair of screws 86 which pass through the sleeve and into the wall of the barrel. The body portion 77 including the handle 84, together with the barrel 72 are capable of lateral swinging movement about the axis of the barrel to accommodate the natural position of the wrist and hand during operation of the instrument mounting.

The pressure spring 68 is disposed within the barrel 72 adjacent its rear end and pressure exerted by the spring is adapted to be applied to the clamping bands 64 of the locking collar 24 through the medium of a sectional thrust rod including a rear rotatable section 88 and a front non-rotatable section 90, both sections being disposed within the barrel 72 in end-to-end relationship. The non-rotatable section 90 is provided with an ear 92 which projects upwardly through a slot 94 provided in the barrel 72 in the upper regions thereof and which slot is of fairly large circumferential extent, in order to give a wide angle of swinging movement to the pistol grip handle 84. The rear rotatable rod section 88 is provided with a slot 96 in register with the slot 78 and through which the trigger member 80 extends. The rear end of the rotatable rod section 88 is slotted as at 98 and a guide pin 100 carried by the barrel 72 projects through the slot 98 so as to connect the barrel and rod section for turning movement in unison while still permitting relative sliding movement of the rod section within the barrel. The trigger member 80 is adapted to bear as at 102 against one end of the slot 96 in the rod section 88 and the forward movement of the trigger member 80 and consequently of the rod section 88, is limited by a stop surface 104 provided on the body 77.

The effective length of the non-rotatable rod section 90 is capable of being varied by means of a pin 106 which extends through a bore 108 provided in the rod section 90 and which has its rear end projecting beyond the end of the rod section 90 and bearing against the end of the pin 106. The forward end of the pin 106 is

threadably received in the forward end of the rod section 90 and an adjusting knob 110 secured to the extreme forward end of the pin 106 is provided so that the pin may be shifted in one direction or the other through the section 90 to increase or decrease its effective length and thus determine the "throw" of the friction bands 64. The trigger member 80 is normally held against the rear end of the slot 96 by means of a spring pressed plunger 112 disposed within a bore provided in the rotatable rod section 88. The rear end of the barrel 72 threadably receives an adjusting plug 114 by means of which the compression of the spring 68 may be varied to in turn vary the pressure applied to the friction bands 64.

From the above description it will be seen that when no pressure is applied to the trigger member 80 the spring 68, acting through the two rod sections 86 and 90, will apply full pressure to the friction bands 64 tending to contract the same on the horizontal arm 14 of the split elbow 10, thereby not only holding the locking collar or brake 24 against turning movement about the horizontal axis of the arm, but also compressing the split end of the arm 14 and spreading the split leg 12 thereof in the manner previously described to lock the split elbow against turning movement about a vertical axis. The instrument support or pad 26 is thus locked against swinging movement about either a vertical or horizontal axis. Upon depression of the trigger member 80 the rotatable rod section 88 will be moved to the left as viewed in Fig. 4, thereby compressing the spring 68 and allowing the rod section 90 to follow the movement of the rod section 88 to release the pressure on the friction bands 64 and permit the split sections 36 and 38 of the composite arm 14 to move away from each other. Pressure of the split sections of the leg 12 against the inner wall surface of the base socket 18 is thus relieved so that the split elbow 10 is capable of turning movement within the base socket. At the same time the relieving of pressure by the friction bands 64 on the arm 14 permits the locking collar 24 to be swung about the horizontal axis of the arm to tilt the instrument support or pad 26 in a fore and aft direction.

The instrument mounting of the present invention is capable of two main types of control. The instrument support or pad 26 may be locked in a fixed position against swinging movement in elevation about the horizontal axis of the arm 14 in a fore and aft direction, or it may be locked against panoramic swinging movement about the vertical axis of the leg 12 and the instrument support may be released for both types of movement simultaneously upon depression of the trigger member 80. Alternatively, the control means may be so conditioned that release of the trigger member 80 is incapable of locking the instrument support 26 against panoramic swinging movement and is capable only of locking the support 26 against fore and aft swinging movement.

The control means for effecting these two types of locking action is best illustrated in Figs. 1 and 5 to 8 inclusive. As shown in these views, a cap member 122 is telescopically received over the end of the split arm 14 and is provided with a centrally disposed wedge cam member 124 having a cylindrical surface 126 somewhat greater than a half-cylinder and having a flat surface 128 extending across the opposed ends of the cylindrical surface 126. The ends of the cylindrical surface 126 are relieved as at 130 to

provide surfaces which are less eccentric with respect to the axis of the cam 124 than is the eccentricity of the cylindrical surface 126. When the cap member 122 is in position on the end of the arm 14, the cam member 124 is adapted to project into the end of the bore 44 and, with the cam assuming the position shown in Fig. 7, the cam is nested within the concave inner surface of the bore 44 so that sufficient clearance is provided whereby the two sections 36 and 38 of the arm 14 may be rocked about the axis of the fulcrum 40 and thus contracted or expanded at will.

When the cam 124 assumes the position shown in Fig. 8, wherein it is at right angles to the position formerly described in connection with Fig. 7, it is nested within both concavities of the two sections 36 and 38 and therefore it serves to maintain these sections separated in their expanded positions. With the cam 124 in this latter position, the friction bands 64 are incapable of compressing the split arm 14 and therefore the two sections 36 and 38 are maintained in such a position that the leg 12 of the elbow 10 is contracted, thus allowing panoramic swinging movement of the instrument support.

An adjusting screw 131 extends through the wall of the section 36, is threaded therein, and has a rounded end 133 capable of projecting into the bore 44 and into the path of movement of the surface of the cam 124. The position of the screw 131 may be adjusted to vary the spread of the sections 36 and 38 of the split arm 14 when the cam 124 assumes the position shown in Fig. 8. Stated in other words, the adjusting screw 131 serves to vary the effective diameter of the bore 44.

The cam 124 is centrally secured to the inside of the cap member 122 by means of a screw 132 which extends through the cap centrally thereof and is threadedly received in the cam 124. The screw 132 has secured thereto an operating lever 134 which is provided with a spring-pressed detent 136 designed for cooperation with a pair of depressions 137 provided on the outer surface of the cap and by means of which the lever 134, and consequently of the cam 124, may be locked in either of two selected positions. Suitable labeling or designations of the position of the lever 134 may be inscribed on the outer surface of the cap 122 and, as shown in Fig. 7, when the lever 134 is in the vertical position labelled "Lock," the cam 124 assumes the position shown wherein freedom of rocking movement between the two sections 36 and 38 is made possible, so that when pressure is applied by the friction bands 64 from the coil spring 68 tending to contract the sections of the split arm 14, the sections of the split leg 12 are spread apart thus applying pressure to the inner wall of the base socket 18 and preventing panoramic swinging movement of the instrument support 26. When the lever 134 assumes the horizontal position shown in Fig. 8 labelled "Pan," the cam 124 assumes the position shown wherein the two sections 36 and 38 are spread apart and are incapable of being moved toward each other. In this position of the cam, the two sections of the leg 12 are positively contracted and no pressure is brought to bear on the inner surface of the base socket 18 so that panoramic swinging movement of the instrument support 26 is at all times available.

The cap 122 is adapted to be securely held in its position over the end of the arm 14 by means

of a locking pin 138 having a knurled head 140 and which extends through an opening 142 in the cap 122 and is threadedly received in the composite arm 14.

I claim:

1. In an instrument mounting, a split elbow structure having a vertical leg adapted to be telescopically received within a vertically extending bore of a base socket, a horizontal arm adapted to receive thereover and support thereon a locking sleeve of an instrument support, and a connecting curved elbow section, said elbow structure being split lengthwise and substantially centrally thereof (see Figs. 1, 5, 7, 10, 11 and 12) and providing two spaced apart complementary half-sections, and means interposed between said sections at spaced points on a straight line extending lengthwise of the vertical leg of said elbow structure and providing a fulcrum axis whereby said sections may be rocked relative to each other about said fulcrum axis whereby movement of the complementary sections of the arm toward each other will cause movement of portions of the complementary sections of the leg away from each other and thereby adapted to force the latter sections into frictional contact with the inner wall of said vertically extending bore of the base socket.

2. In an instrument mounting, a split elbow structure having a vertical leg adapted to be telescopically received within a vertically extending bore of a base socket, a horizontal arm adapted to receive thereover and support thereon a locking sleeve of an instrument support, and a connecting curved elbow section, said elbow structure being split lengthwise and substantially centrally thereof and providing two spaced apart complementary half-sections, and a relatively thin web having at least a portion thereof formed on one of said sections and bearing against the other section and extending along a straight line adjacent and parallel to the inner edges of the leg portions of said elbow structure and providing a fulcrum axis about which said sections may be rocked throughout a limited extent relative to each other.

3. A split elbow structure for instrument mountings of the character described having an outwardly extending leg at one end thereof, an outwardly extending arm at the other end thereof, and an interconnecting curved elbow portion medially thereof, said elbow structure being split lengthwise and substantially centrally thereof to provide two spaced apart complementary half-sections, and a relatively thin web of straight line configuration extending along the region of the inner edges of the composite leg sections between said sections and providing a fulcrum axis about which the sections may be tilted relative to each other.

4. A split elbow structure for instrument mountings of the character described having a leg and an arm extending at angles to each other, and an interconnecting curved elbow section, said elbow structure being split lengthwise and substantially centrally thereof to provide spaced apart complementary half-sections, and a relatively thin web of straight line configuration extending along the region of the inner edges of the composite leg sections and transversely across the elbow section and providing a fulcrum axis about which said sections may be rocked relative to each other.

5. A split elbow structure for instrument mountings of the character described having a

leg and an arm extending at angles to each other, and an interconnecting curved elbow section, said elbow structure being split lengthwise and substantially centrally thereof to provide complementary half-sections, and a relatively thin linear flange of straight line configuration formed on each of said sections and extending along the respective inner edge of the leg portion thereof and transversely across the elbow section thereof to hold said complementary sections in spaced relation to each other, said flanges being in direct opposition and edge-to-edge contact with each other and providing a fulcrum axis about which the sections may be tilted relative to each other.

6. A split elbow structure for instrument mountings of the character described having a leg and an arm extending at right angles to each other, and an interconnecting curved 90° elbow section, said elbow structure being split longitudinally and substantially centrally to provide complementary half-sections, and a relatively thin web of straight line configuration extending across the region of the inner edges of the composite leg sections and transversely across the elbow section and axis of the arm section, said web having a portion thereof formed on one of said sections and another portion thereof formed on the other section with the medial regions of the web being fractured along its entire length to provide irregular mating surfaces which constitute an infinite series of available fulcrum points arranged generally in alignment for rocking movement of the two sections relative to each other.

7. An instrument mounting comprising a base socket member having a vertical cylindrical wall, a split elbow structure having a vertical leg adapted to be telescopically received within said socket and a horizontal arm adapted to receive thereover and support thereon a locking sleeve of an instrument support, said elbow structure being split lengthwise and substantially centrally thereof and providing two complementary half-sections, said sections being provided on their inner faces with a fulcrum bearing whereby rocking movement of the sections on each other to move the complementary sections of the horizontal arm toward each other and force the complementary sections of the vertical leg into frictional holding engagement with the cylindrical wall of said socket, the complementary sections of said horizontal arm being recessed internally to provide a substantially cylindrical bore within the composite arm, a cam telescopically received in said bore and having a generally semi-cylindrical outer surface designed for wedging engagement with the opposed walls of said bore, said cam when in one position of adjustment having its semi-cylindrical surface in spreading engagement with the opposed walls of said complementary sections of the horizontal arm, and when in another position of adjustment having its semi-cylindrical surface substantially wholly contained within one wall of said bore to relieve the pressure applied to said walls and permit rocking movement of the sections relative to each other, and manual means for moving said cam to either of said positions of adjustment.

8. An instrument mounting comprising a base socket member having a vertical cylindrical wall, a split elbow structure having a vertical leg adapted to be telescopically received within said socket and a horizontal arm adapted to receive

11

thereover and support thereon a locking sleeve of an instrument support, said elbow structure being split lengthwise and substantially centrally thereof and providing two complementary half-sections, said sections being provided on their inner faces with a fulcrum bearing whereby rocking movement of the sections on each other to move the complementary sections of the horizontal arm toward each other and force the complementary sections of the vertical leg into frictional holding engagement with the cylindrical wall of said socket, the complementary sections of said horizontal arm being recessed internally to provide a substantially cylindrical bore within the composite arm, a cup-shaped cap member telescopically receivable over the forward end of said arm, said cam having a generally cylindrical outer surface designed for wedging engagement with the opposed walls of said bore, said cam when in one position of its adjustment for its semi-cylindrical wall in spreading engagement with the opposed walls of said complementary sections of the horizontal arm, and when in another position of adjustment being substantially wholly contained within one wall of said bore to relieve the pressure applied to said walls and permit rocking movement of the sections relative to each other, an operating finger secured to said cam and projecting through the wall of said cap member and movable with the cam between two positions of adjustment and detent means for holding said operating finger in either position of adjustment.

9. An instrument mounting comprising a base socket member having a vertical cylindrical wall, a split elbow structure having a vertical leg adapted to be telescopically received within said socket and a horizontal arm adapted to receive thereover and support thereon a locking sleeve of an instrument support, said elbow structure being

12

split lengthwise and substantially centrally thereof and providing two complementary half-sections, said sections being provided on their inner faces with a fulcrum bearing whereby rocking movement of the sections on each other to move the complementary sections of the horizontal arm toward each other and force the complementary sections of the vertical leg into frictional holding engagement with the cylindrical wall of said socket, the complementary sections of said horizontal arm being recessed internally to provide a substantially cylindrical bore within the composite arm, a cup-shaped cap member telescopically receivable over the forward end of said arm and having a cylindrical flange encompassing said arm for limiting the spreading movements of the complementary sections thereof, a cam mounted for rotation centrally within said cap member and projecting into said bore, said cam having a generally semi-cylindrical outer surface designed for wedging engagement with the opposed walls of said bore, said cam when in one position of adjustment having its semi-cylindrical wall in spreading engagement with the opposed walls of said complementary sections of the horizontal arm, and when in another position of adjustment having its semi-cylindrical surface substantially wholly contained within one wall of said bore to relieve the pressure applied to said walls and permit rocking movement of the sections relative to each other, means extending through said cap member for moving said cam to either of its two positions of adjustment, and means for securing said cap member to one of the complementary sections of said arms.
